UNITED STATES PATENT OFFICE.

JAMES FARASEY, OF CLEVELAND HEIGHTS, OHIO.

DRYING APPARATUS.

Application filed February 20, 1922. Serial No. 537,733.

To all whom it may concern:

Be it known that I, JAMES FARASEY, a citizen of the United States, residing at Cleveland Heights, in the county of Cuyahoga and State of Ohio, have invented a certain new and useful Improvement in a Drying Apparatus, of which the following is a full, clear, and exact description, reference being had to the accompanying drawings.

This invention relates to driers of the general type which includes an inclined heated rotary drum provided with lifting flanges therein and having heat-conducting flues by means of which the hot gases are brought into contact with the material as it advances.

In driers of the type described, it is customary to provide suitable hood members through which the hot gases are conducted from the furnace chamber to the interior of the drum. In constructions heretofore employed, the hoods have been directly secured to the inside of the heating drum. The drums are made of rolled plate and as the flow of hot gases is concentrated on this plate adjacent the opening to the hood, the plate about the hoods after some time, becomes fire cracked and in such condition that the efficiency of the drier is impaired. Consequently, after a drier has been used for some time, it becomes necessary to cut away the corroded portion of the plate and patch the drum adjacent the point of attachment of the hood.

I have found that by providing a cast iron flanged collar for connecting the hood to the drum arranged so that the flange covers the exterior of the drum adjacent the aperture, that the difficulty mentioned above is overcome. The flange surrounds the opening to the hood and thus protects the plate and being made of cast iron withstands the action of the fire better than rolled plate. The life of the drier is thus greatly increased and moreover should the flanged collar become unfit for further use, it can be readily removed and another collar substituted without the necessity of patching the plate, as is the case in the present construction.

An object of the invention is to provide means whereby the drum of a drier adjacent the outlets to the hoods is protected from fire cracking and general deterioration.

Another object of my invention is to provide an improved hood or elbow for use in

connection with heating drums so constructed that the hood may be readily replaced should any of its parts become damaged.

A further object of my invention is to provide an improved connecting means for attaching a heat-conducting hood to a drier arranged so that the hood may be readily replaced if necessary while the drum will be protected at its point of connection with the hood.

Further and other objects of the invention will be apparent from the following description, taken in connection with the accompanying drawings wherein Fig. 1 is a central sectional view of a drier showing my invention applied thereto; Fig. 2 is an elevation of the hood embodying my invention; Fig. 3 is a section on the line 3-3, Fig. 2; Fig. 4 is a section through the drier showing my improved hoods in elevation and Fig. 5 is a section on the line 5-5, Fig. 2.

Referring to the drawings by reference numerals, I have shown at 10 a drying drum of the type with which my invention is adapted to be used. This drum may be mounted to rotate on suitable rollers; the rotation being effected in any well known manner. The drum is indicated as mounted above a furnace 11 provided with a furnace chamber 12 having apertures 14 in its upper wall through which the heated products of combustion pass.

The material is usually fed to the drier through a hopper 15 whence it passes by gravity down the inclined surface of the drum 10. Suitable lifting blades 16 for causing agitation of the mass being dried may be provided on the inner periphery of the drum if desired. After passing through the apertures 14, the hot gases enter the chamber 17 whence they are conducted through heat conduits or hoods 20 to the interior of the drum.

The hoods 20 which form the subject matter of the present application are each shown as comprising an elbow-shaped portion 21 which flares at its end as indicated at 22. The flared end is provided with a plurality of outwardly extending lugs 23 which are provided with suitable apertures therethrough. To prevent material being dried from entering the hood, and at the same time to provide an outlet for the gases, I provide a cover member 25 therefor. This cover member is shown as provided on its in-

terior with lugs 26 which align with the projections 23 on the hood. Suitable bolts 27 serve to removably hold the covers on the hoods. The path of the heated gases from the hood 20 to the interior of the heating drum is indicated by arrows in Fig. 5.

The other end of the hood 20 is indicated as provided with an enlargement as at 28 and is rabbeted as at 29 to removably receive a collar 34 therein. This collar 34 is provided with a flange 35 which is shown as secured to the drum 10 by suitable rivets 33. The hood may be removably secured to the collar 34 by suitable bolts 30 as shown. The flanged collar 34 being made of cast iron, or cast steel protects the plate 10 from the hot gases which flow into the drum. In former constructions wherein a flange integral with the hood was secured upon the interior of the drum, the plate 10 adjacent the opening to the hood was unprotected and soon became damaged.

My invention overcomes the difficulty mentioned and also allows a hood or flange collar to be very easily replaced if necessary with a minimum of time and expense. It will therefore be apparent that my invention lengthens the life of driers and allows repairs to be quickly and easily effected.

I claim:

1. In combination, a drying drum having an opening in the wall thereof, a hood, and means to connect said hood to the drum, said means comprising a collar detachably secured to the hood, said collar projecting through said opening in the drum and having a flange thereon which is secured to the exterior of the drum.

2. The combination with a furnace of a drying drum having an aperture therein through which products of combustion from the furnace may pass into the interior of the drum, a hood within the drum, and means to connect said hood to the drum, said means including a member which surrounds the aperture in the drum on the exterior of the drum to protect the latter from the destructive effects of the hot gases.

3. A drying cylinder having an inlet for material at one end and an outlet for material at the other end, and having an opening through the side of said cylinder, an annular metal ring surrounding said opening on the exterior of the drum, an internal heat conduit secured to said ring, and a furnace so arranged that the hot gases strike the exterior of the drum.

4. The combination with a furnace, of a drying drum having an aperture through its wall through which hot gases may pass from the furnace into the interior of the drum, and a casting which surrounds the aperture in the drum on the exterior thereof and projects into the interior to protect the drum from the corroding effects of the hot

gases, and a heat conduit within the drum in registration with said aperture.

5. A drying cylinder having an inlet for material and an outlet for material, and having an opening through the side of said cylinder, a cast ring surrounding said opening and secured to the exterior of the cylinder and having a sleeve extending into the interior, and a heat conduit removably secured to said sleeve within the cylinder.

6. A drying cylinder having an inlet for material at one end and an outlet for material at the other end and an opening through the side of said cylinder, a flanged sleeve extending through said opening, and having its flange portion secured to the exterior of the cylinder, and a hood within the cylinder secured to said sleeve.

7. The combination with a furnace, of a drying cylinder having an inlet for material at one end and an outlet for material at the other end and openings through the side of said cylinder for admission of hot gases from the furnace, flanged sleeves having their flanges secured on the exterior of the cylinder around the openings and their sleeve portions extending through said openings, and hoods removably secured to said sleeves within the cylinder.

8. In a drying furnace, the combination of a drying container having an aperture therein, and a flanged cast iron collar inserted in said aperture, the flange of said collar being secured to the exterior of said container about the aperture and the sleeve portion of the collar extending into the interior of the container, and a conduit within the container overlapping the sleeve part of said collar, and bolts passing through the overlapped portions of the collar and conduit.

9. In a drying furnace, the combination of a drying container having an aperture therein, and a flanged cast collar inserted in said aperture, the flange of said collar being secured to the exterior of said container about the aperture, the collar having a sleeve extending through the aperture, and a conduit removably secured to said sleeve, said conduit and sleeve overlapping and one of them being rabbeted at its end to provide a shoulder against which the other abuts.

10. In a drying furnace, a drying container having an aperture therein, a cylindrical collar inserted in said aperture and having a flange secured to said container, a conduit secured to the cylindrical portion of the collar, the conduit being rabbeted adjacent its engaged end to receive the collar, said conduit being substantially L-shaped and having a cover plate removably secured upon its other end.

11. The combination with a furnace, of a drying drum having an aperture therein through which products of combustion from

the furnace may pass into the interior of the drum, a hood within the drum adapted to receive and direct such products of combustion, and an annular protecting member 5 on the exterior of the drum surrounding said aperture.

12. The combination with a furnace, of a metal drum having an aperture therein through which products of combustion from 10 the furnace may pass, a hood within the drum in registration with the aperture, and a cast iron ring on the exterior of the drum surrounding the aperture and protecting it from the destructive effects of the hot gases.
13. The combination with a furnace, of a rotary drying drum above it against which the hot products of combustion impinge, said drum having a number of apertures 15 through its wall through which such hot 20 products may pass into the interior of the

drum, and cast metal rings which surround the respective apertures in the drum on the exterior thereof to protect the drum from the corroding effects of the hot gases, and heat conduits within the drum registering 25 with said apertures.

14. The combination with a furnace, of a drying cylinder in proximity thereto, having an inlet and an outlet for material, and openings through the side of said cylinder 30 for admission of hot gases from the furnace, cylindrically curved rings on the exterior of the cylinder, riveted to it and extending around the openings, and hoods secured 35 within the cylinder in registration with said openings, respectively.

In testimony whereof, I hereunto affix my signature.

JAMES FARASEY.
